LABEL

Floyd Matthews, Fairlawn, N. J.

Application October 18, 1934, Serial No. 748,939

3 Claims. (Cl. 40—20)

The present invention relates to new and useful improvements in labels particularly for wearing apparel and has for its primary object to provide a label embodying novel means for folding said label preparatory to its attachment to the garment or other article in a manner to materially reduce the cost and labor which this operation usually involves.

Other objects of the invention are to provide a label for garments and other articles which will be simple in construction, durable, attractive in appearance and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:—

Figure 1 is a view in front elevation, showing a label in accordance with the present invention before it is folded.

Figure 2 is a front elevational view of the label after it is folded.

Figure 3 is a view on an enlarged scale and in rear elevation of a portion of the label before the folding operation takes place.

Referring now to the drawing in detail, it will be seen that the embodiment of the invention which has been illustrated comprises a foldable sheet 1 having end flaps 2 joined thereto along fold lines 3. The selvage of the label is designated by the reference numeral 4.

Mounted loosely on the longitudinal edges of the label are draw strings 5 which are slidably attached to the selvage 4 on the sheet 1 adjacent the fold lines 3 by loops 6, as illustrated to advantage in Figure 3 of the drawing. From the loops 6, the end portions of the draw strings 5 extend across the fold lines 3 and are turned at right angles and then folded upon themselves and anchored to the end flaps 2, as at 7.

To attach the label, said label may be held in any suitable manner and the draw strings 5 are pulled outwardly in opposite directions by any

suitable means through the loops 6 in a manner to draw the end flaps 2 from the position shown in Figure 1 of the drawing to a position adjacent the back of the sheet 1, as indicated in dotted lines in Figure 2 of the drawing. The label is 5 then ready to be attached to the garment or other article. The means 7 for attaching the draw strings 5 to the end flaps 2 is preferably in the form of stitches which extend through said flaps 2, as seen in Figure 1 of the drawing. 10 After the folding operation has been completed, the attaching means 7 is, of course, concealed behind the sheet 1 of the label. By folding the end portions of the draw strings 5 and securing said folded end portions transversely on the end 15 flaps 2 of the label said draw strings are prevented from pulling out the stitches 7.

It is believed that the many advantages of a label constructed in accordance with the present invention will be readily understood, and although a preferred embodiment of the invention is as illustrated and described, it is to be understood that changes in the details of construction and in the combination and arrangement of parts may be resorted to which will fall within the 25 scope of the invention as claimed.

What is claimed is:—

1. A label comprising a foldable sheet, and draw strings anchored to marginal portions of said sheet and slidably connected to said sheet 30 at points inwardly of said marginal portions for folding said marginal portions on said sheet.

2. A label comprising a foldable sheet, and draw strings having their end portions anchored to certain of the marginal portions of said sheet, 35 said draw strings further being slidably connected to said sheet at points inwardly of said certain marginal portions for folding said certain marginal portions on said sheet.

3. A label comprising a foldable sheet, loops 40 on said sheet adjacent the ends thereof, and draw strings extending slidably through the loops and anchored to the ends, said draw strings constituting means for folding the end portions of the sheet.

FLOYD MATTHEWS.
